UNITED STATES PATENT OFFICE.

JOHN H. KINEALY, OF FERGUSON, MISSOURI.

VENTILATING SYSTEM.

1,202,853.

Specification of Letters Patent. Patented Oct. 31, 1916.

Application filed September 2, 1915. Serial No. 48,666.

To all whom it may concern:

Be it known that I, JOHN H. KINEALY, a citizen of the United States, residing at Ferguson, in the county of St. Louis and State of Missouri, have invented a new and useful Improvement in Ventilating Systems, of which the following is a full, clear, and exact specification, reference being had to the accompanying drawings, which form a part thereof.

My invention relates to ventilating systems for places occupied by human beings in which it is desirable to have the air in as pure a condition as possible, and to prevent the air therein from becoming stagnant or dead; and my invention relates particularly to those systems of ventilation in which a fan or similar means is used for causing a flow of air to the place to be ventilated.

The object of my invention is to provide a ventilating system by means of which an adequate and proper amount of warm air may be supplied to the place to be ventilated and, in addition thereto, to provide means whereby at stated or predetermined intervals the place to be ventilated may be flushed by means of cool air so as to destroy any stratification of air which may be formed in the place to be ventilated and thus prevent the air from becoming dead; and a further object of my invention is to provide a ventilating system that is especially applicable to schools whereby all the rooms of schools may be simultaneously flushed at regular predetermined intervals with cool air for a fixed period of time.

In ventilating systems used for schools and similar buildings it is customary to cause a flow of air through the rooms by means of a fan and to control the temperature in each room by means of a thermostat which controls the operation of dampers whereby the temperature of the air admitted for ventilation may be varied to suit the requirements of the room. This is especially true of those ventilating systems in which all or part of the heating of the rooms is done by the air supplied for the ventilation. The air is introduced into the various rooms in such a way as to avoid drafts, with the result that in a short time the air appears to become arranged in strata and the occupants experience a feeling of heaviness and

drowsiness simply because the air seems to lack life. In order to revivify and freshen the air in the rooms it has been customary for the teachers to flush out the various rooms by opening the windows. In most cases, however, when the teacher in charge of one room opens the windows of that room and keeps them open for a few minutes the ventilating system of the entire building becomes deranged because the system is put in an unbalanced condition, due to the opening of the windows in the room being flushed. One object of my invention, therefore, is to provide a system of ventilation for a plurality of rooms whereby all of the rooms may be simultaneously flushed in such a manner that the flushing will be done at predetermined or stated intervals and without any care or attention upon the part of the occupants of any of the rooms.

My invention is fully shown in the accompanying drawings where similar letters are used to designate similar parts.

Figure 1 is a sectional view of a building equipped with a ventilating system embodying my invention; Fig. 2 is an enlarged sectional view of one of the details of the apparatus used in Fig. 1; Fig. 3 is a view seen looking at the apparatus shown in Fig. 1 from the left thereof; Figs. 4, 5 and 6 are views showing details of parts of the apparatus used in Fig. 1.

Referring to the figures, A is a fan mounted upon a suitable foundation and provided with a band wheel A', by means of which it may be driven by a belt from a suitable motor, not shown.

B is a heater by means of which heat is supplied to that part of the air from the fan which enters the warm air chamber C. The heater B may be of any one of the well known forms of heaters used for heating air in ventilating systems, and is connected by suitable pipes, not shown in the drawings, to a source of supply of heat. Beneath the warm air chamber C there is located a cool air chamber D into which air passes from the fan A without passing over the heater B.

E is a branched duct through which air is supplied to one of the rooms to be ventilated and which is connected to the warm air chamber C by means of the branch F and to the cool air chamber D by means of the branch G.

H is a damper which controls the flow of air from the warm air chamber C into the duct E; and I is a damper which controls the flow of air from the cool air chamber D into the duct E. These dampers are pivotally supported so that they may be turned to any position so as to regulate the flow of air from the chambers C and D through the duct E into the room. These dampers are preferably connected to one another by means of a link K and one of them, in the apparatus shown in the drawings, the damper I, has attached to it a crank arm L which is connected by means of a link M to the arm N of the pressure motor O.

P is a source of supply of air under pressure and R is a pipe leading from an outlet pipe X to a thermostat Q located in a room to which the duct E leads.

T is a branch pipe leading from the pipe R to the motor O.

U is a restricting fitting, shown in section in Fig. 2, which has through it a restricted passage u.

Thermostats are so well known that it is not necessary to describe in detail the construction of the thermostat Q, but it suffices to say that Q is provided with a restricted vent opening which is larger than the restricted opening u in the fitting U, and usually the vent in the thermostat Q is open fully when the damper F controlling the flow of air from the warm air chamber is fully opened and the damper I controlling the flow of air from the cool air chamber is completely closed. When the temperature in the room has been raised to a certain predetermined point the thermostat Q acts to close the vent therein and then air passes through the restricted opening u of the fitting U into that part of the pipe R between the thermostat and the fitting U and through the pipe T to the motor O, until the pressure in these parts has become sufficient to cause the motor O to operate to force outwardly the arm N and by means of the link M and the crank L to cause the dampers to be moved so that the damper H will be put into closed position and the damper I to be put into open position, thus preventing the flow of warm air through the duct E into the room and allowing the flow into the room of cool air.

It is sometimes desirable to regulate the temperature in the cool air chamber D and this may be done by providing a pivotally mounted damper Y in the partition Q between the warm air chamber C and the cool air chamber D. This damper is operated by means of a motor O' controlled by a thermostat Q'. The motor O' and the thermostat Q' are connected to the source of supply of air P by means of the pipe R'' which is provided with a restricting fitting U. The thermostat Q' controls the motor O so that

the damper Y is opened to allow the warm air to pass from the warm air chamber into the cool air chamber when the temperature in the latter is less than it should be, and to close the damper Y to prevent the flow of warm air into the chamber D when the temperature therein is greater than it should be. By means of the thermostat Q' the temperature in the cool air chamber may be maintained substantially constant at any predetermined point between the temperature of the air leaving the fan and that of the air in the warm air chamber C.

W is a valve in the pipe R between the thermostat Q and the branch pipe T. This valve is normally open but its stem is connected to the motor V by means of which the valve may be closed. When the valve W is closed the thermostat Q is operatively disconnected from the ventilating system and air leaks through the restricted opening in the fitting U so that a pressure is created in the pipe T and the motor O in such a way that the motor O operates to cause the damper H to assume a closed position and the damper I to assume an opened position, thus allowing cool air only to be supplied through the duct E to the room. As long as the valve W is kept closed cool air only can be supplied to the room and thus the room will be flushed during the period that the valve W is kept closed.

S is a controller connected to the outlet X of the tank P by means of the pipe R' which is provided with a restricting fitting U.

T' is a pipe connecting the motor V to the pipe R' at a point between the fitting U and the controller S.

The controller S is shown in detail in Figs. 4, 5 and 6, where a represents a casing having a perforated hinged door a'. Inside of the casing there is placed a motor b having a revolving spindle d which carries a circular plate c. The motor b is preferably an ordinary spring motor of the clock type so arranged that the spindle d is given a uniform motion of rotation for a considerable period of time. The spindle d has fixed to it a flange e and has its outer end threaded to receive the milled nut f. The plate c is held in fixed position between the flange e and the nut f so that it revolves with the spindle d, but when the nut f is loosened the plate c may be adjusted or turned to any desired position on the spindle d.

G is a cam formed on the face of the plate c adjacent to its perimeter.

h is a bell crank lever attached by means of the bent spring k to the base piece i. This base piece i is provided with a projecting shank j which is threaded interiorly and exteriorly.

l is a nut engaging with the threads on

the exterior of the shank *j* and which serves to hold the base piece *i* in fixed position. The upper end of the pipe *R'* is adapted to engage with the interior threads of the 5 shank *j*.

m is a nipple having therethrough a restricted opening by means of which communication is established between the pipe *R'* and the interior of the casing *a*. The 10 opening in the nipple *m* serves as a vent for the pipe *F'*, and is larger than the restricted opening *u* in the fitting *U*.

n is a bearing screw which engages with a threaded opening in the vertical leg of the 15 bell crank *h* and which is provided with a suitable lock nut whereby when the screw *n* is adjusted it may be held in adjusted position. The end of the screw *n* is rounded and adapted to bear on the face of the plate *c*. The screw end is so adjusted that when it bears on the surface of the cam *g* the bell crank *h* is moved so that its horizontal arm is pressed down so as to close the vent opening in the nipple *m*, and when the cam *g* is moved to one side of the screw *n* the spring *k* will move the bell crank lever *h* so that the opening in the nipple *m* will not be closed. When the vent in the nipple *m* is open air will escape from the pipe *R'* into the casing *a* from which it will pass through the openings in the door *a'*. Since the vent in the nipple *m* is larger than the restricted opening in the fitting *U* in the pipe *R'*, when this vent is open no pressure is created in the pipe *T'* and the motor *V* does not operate, and the valve *W* remains open. When however, the vent in the nipple *m* is closed pressure accumulates in the pipe *R'* and in the motor *V*, and the latter is caused to operate to close the valve *W*. The plate *c* is preferably made to revolve in the direction of the hands of a clock.

The operation of the system of ventilation is as follows: The fan *A'* is set in motion and air is drawn from a suitable source of supply which may be the outside of the building or it may be a room or chamber in which the air is warmed or washed or otherwise treated. Part of the air leaving the fan passes over the heater *B* into the warm air chamber, and from there through the branch *F* it passes the chamber *H* into the duct *E* and through this into one of the rooms of the building. Part of the air from the fan passes directly into the cool air chamber *D*. By means of the thermostat *Q* the movement of the damper *Y* is controlled so that as much warm air is allowed to pass from the warm air chamber *C* into the cool air chamber *D* as is necessary to maintain the temperature of the cool air chamber at the desired point. The thermostats *Q* control the action of the motors *O* so as to cause them to operate the dampers *T* and *I* to allow cool air or warm air

to be supplied to the various rooms as the temperature therein may require. The controller *S* is placed in any desired part of the building, but preferably in one of the rooms to which air is supplied. The motor *b* being set in operation, the plate *c* is caused to turn and when the cam *g* is brought under the end of the screw *n* the bell crank lever *h* is moved to close the vent in the nipple *m* and then air under pressure flows from the source of supply *P* into the pipes *R'* and *T'* and into the motors *B* and causes these latter to operate to close the valves *W*. By the closing of the valves *W* all the thermostats are simultaneously operatively disconnected from the motors which they control. As soon as the valves *W* are closed air passes through the pipes *R'* into the pipes *T'* and from there into the motors *O* and causes these latter to operate to close the dampers *H* and to open the dampers *I*, thus admitting a flow of air from the cool air chamber to all the rooms of the building at the same time. The surface of the cam *g* on the plate *c* is made of such a length that the end of the screw *n* will remain in contact with it for as long a period as desired, and thus keep the vent opening in the nipple *m* closed for a fixed period. As long as the vent opening in the nipple *m* is kept closed, cool air only will be supplied to the rooms and during this period of time the rooms will be flushed. The motor *b* may be designed to cause the plate *c* to make as many revolutions per hour as desired, but in the specific form shown in the drawings the plate *c* is supposed to revolve about once every hour and the operative surface of the cam *g* is made of such a length that the rooms will be flushed during a period of approximately five minutes.

If at any time it should be necessary or desirable to flush the building other than at a time at which it would normally be flushed by the operation of the controller, the nut *f* may be loosened and the plate *c* turned by hand so as to cause the cam *g* to act upon the bell crank lever *h* to close the vent in the nipple *m* and thus bring about the flushing operation of the rooms.

It is evident that the motor *b* may be of any suitable form, since all that is necessary is that it shall be able to drive the plate *c* with a substantially uniform motion.

I have shown my ventilating system applied to three rooms of a building, but it is evident that it may be applied to any number of rooms and all of the rooms may be simultaneously flushed with cool air.

I do not mean to restrict myself to the exact details of apparatus shown in the drawings since it is evident that different methods may be used for simultaneously operatively disconnecting the thermostats from their respective motors.

What I claim as new and desire to secure by Letters Patent, is:

1. In combination with a ventilating system for a room, dampers for controlling the temperature of the air supplied to said room, a fluid pressure motor for operating said dampers, a thermostat controlling the accumulation of pressure in said motor, and means whereby at stated intervals said motor is automatically caused to operate independent of said thermostat to move said dampers to a predetermined position and there maintain them during a fixed period. 50
2. In combination with a ventilating system for a plurality of rooms, dampers for each room whereby the temperature of the air supplied thereto is controlled, a fluid pressure motor for each room for operating the dampers therefor, a thermostat in each room controlling the accumulation of pressure in the motor therefor, and means whereby at stated intervals all of said motors are automatically and simultaneously caused to operate independent of their respective thermostats to move said dampers to a predetermined position and there maintain them during a fixed period. 60
3. In combination with a ventilating system for a room, dampers for controlling the temperature of the air supplied to said room, a fluid pressure motor for operating said dampers, a thermostat controlling the accumulation of pressure in said motor, and means whereby at stated intervals pressure is automatically caused to be accumulated and maintained for a fixed period in said motor independent of said thermostat. 65
4. In combination with a ventilating system for a plurality of rooms, dampers for each room whereby the temperature of the air supplied thereto is controlled, a fluid pressure motor for each room for operating the dampers therefor, a thermostat in each room controlling the accumulation of pressure in the motor therefor, and means whereby at stated intervals pressure is automatically caused to be simultaneously accumulated and maintained for a fixed period in all of said motors. 70
5. In combination with a ventilating system for a room, dampers for controlling the temperature of the air supplied to said room, a fluid pressure motor for operating said dampers, a tube connecting said thermostat to said motor, a valve in said tube, and means whereby at stated intervals said valve is automatically closed and maintained in a closed position during a fixed period. 75
6. In combination with a ventilating system for a plurality of rooms, dampers for each room for controlling the temperature of the air supplied thereto, a fluid pressure motor for each room for operating the dampers therefor, a thermostat in each room controlling the accumulation of pressure in the motor therefor, a tube connecting each thermostat with its respective motor, a valve in each tube, and means whereby at stated intervals all of said valves are automatically closed and maintained in a closed position 80 during a fixed period. 85
7. In combination with a ventilating system for a plurality of rooms, dampers for each room for controlling the temperature of the air supplied thereto, a fluid pressure motor for each room for operating the dampers therefor, a thermostat in each room controlling the accumulation of pressure in the motor therefor, a tube connecting each thermostat with its respective motor, a valve in each tube, a fluid pressure motor for operating each of said valves, and means whereby at stated intervals pressure is automatically caused to be simultaneously accumulated and maintained for a fixed period in said motors for operating said valves. 90

In witness whereof I have signed my name to this specification.

JOHN H. KINEALY.
